UNITED STATES PATENT OFFICE

153,488

DESIGN FOR A COMBINATION CHAIR, IRONING BOARD, AND STEPLADDER

Philipp B. Balavny, Hatboro, Pa.

Application April 3, 1947, Serial No. 138,144

Term of patent 14 years

(Cl. D15—1)

To all whom it may concern:

Be it known that I, Philipp B. Balavny, a citizen of the United States of America, residing at Hatboro, in the county of Montgomery and State of Pennsylvania, have invented a new, original, and ornamental Design for a Combination Chair, Ironing Board, and Stepladder, of which the following is a specification, reference being had to the accompanying drawing, forming a part thereof, wherein:

Figure 1 is a perspective view of the combination chair, ironing board and stepladder arranged for use as a kitchen chair, showing my new design;

Figure 2 is a side elevation of the combination chair, ironing board and stepladder arranged for use as a kitchen chair;

Figure 3 is a front elevation of the combination chair, ironing board and stepladder arranged for use as a kitchen chair;

Figure 4 is a side elevation of the combination chair, ironing board and stepladder arranged for use as an ironing board, and

Figure 5 is a side elevation of the combination chair, ironing board and stepladder arranged for use as a stepladder.

I claim:

The ornamental design for a combination chair, ironing board, and stepladder, as shown.

PHILIPP B. BALAVNY.
